SEMIAUTOMATIC STARTER CONTROL

Paul H. Maurer, Elmira, N. Y., assignor to Eclipse
Machine Company, Elmira Heights, N. Y., a
corporation of New York

Application March 25, 1933, Serial No. 662,756

2 Claims. (Cl. 290—38)

This invention relates to a semi-automatic starter control and more particularly to a starter control of the type in which the starting operation is initiated by the closure of a manual switch such as the ignition switch of the engine to be started, restarting in case of engine stall being secured by opening and reclosing the ignition switch.

It is an object of the present invention to provide a semi-automatic starter control which insures continuous cranking until the engine starts and then automatically opens the starter switch.

It is another object to provide such a device which after an initial start positively prevents reactivation of the starting mechanism until the ignition switch is opened, and reclosed.

A further object is to provide such a device which requires no additional manual switch nor any special form of ignition switch.

Another object is to provide such a device which is simple and economical in construction and both reliable and efficient in operation.

Further objects and advantages will be apparent to those skilled in this art from the following description taken in connection with the accompanying drawing in which:

Fig. 1 is a diagrammatic representation of a preferred form of the invention showing the parts in normal or idle position; and

Fig. 2 is a similar view of a second embodiment of the invention.

Referring first to Fig. 1, there is illustrated a starting system for an internal combustion engine, not illustrated, including a battery 1 grounded at 2 and connected by a lead 3 to a magnetic starting switch indicated generally by numeral 4 which in turn is connected by lead 5 to a starting motor SM which is grounded at 6 to complete the starting circuit.

The magnetic starting switch comprises a solenoid 7 which is included in a control circuit comprising the battery 1, lead 3, manual switch 8 which may be the ignition switch of the engine to be started, lead 9, lead 11 and normally closed contacts 12 and 13, the latter being movably mounted on an armature 14 pivoted and grounded at 15 to complete the control circuit.

Means responsive to a running function of the engine, for opening said contacts to cause the starting switch 4 to open, is provided in the form of a solenoid 16 grounded at one end at 17 and connected at the other end by a lead 18 to the usual engine driven generator G which is grounded as indicated at 19. Solenoid 16 is arranged adjacent the armature 14 whereby energization of

the generator when the engine becomes self-operative causes the solenoid to move armature 14 to open contacts 12, 13.

Electromagnetic lock-out means under the control of the operator are provided for holding open the contacts 12, 13 after an initial start, in the form of a second solenoid 20 also arranged to attract the armature 14, said solenoid being grounded at one end at 17 and being connected by a lead 21 to the lead 11 of the control circuit. It will thus be seen that when contacts 12, 13 are opened, the circuit of the lock-out solenoid 20 which is bridged around said contacts is cut into the control circuit to be energized thereby and maintain the contacts open. The resistance of the circuit of solenoid 20 is arranged to be sufficient to cause substantial deenergization of the solenoid 7 of the starting switch and therefore cause opening of the starting switch when contacts 12, 13 are open. This may be accomplished by designing the solenoid 20 so as to have sufficient resistance for the purpose, or a suitable resistance 22 may be inserted in the solenoid circuit.

In the operation of this embodiment of the invention, closure of the manual switch 8, which may preferably be the ignition switch for the internal combustion engine, completes a circuit from battery 1 through leads 3, 9, solenoid 7, lead 11, contacts 12, 13, armature 14 and ground 15 whereby solenoid 7 is energized and starting switch 4 closed. This completes the starting circuit from battery 1 through leads 3, 5 to starting motor SM whereby the engine is cranked in the usual manner.

When the engine starts, the generator G builds up and energizes solenoid 16 which attracts armature 14 and opens contacts 12, 13. This cuts the circuit of lock-out solenoid 20, including the resistance 22, into the control circuit whereby the solenoid 7 is weakened so as to cause starting switch 4 to open, whereas solenoid 20 is sufficiently energized to hold contacts 12, 13 open. This condition is maintained as long as the manual switch 8 remains closed. In order to secure a restart of the engine, it is merely necessary, to open the manual switch 8, thus deenergizing lock-out solenoid 20 and allowing contacts 12, 13 to close. Reclosure of manual switch 8 then causes reoperation of the starting mechanism as above described.

In Fig. 2, an embodiment of the invention is illustrated in which the intake vacuum of the engine is utilized to cause the initial opening of the control contacts 12, 13. The parts of the

starting and controlling circuits in this embodiment of the invention are the same as illustrated in Fig. 1 and are similarly numbered. Armature 14, however, instead of being opened 5 by means of a generator coil, is suitably connected as by means of a link 23 to a piston 24 slidably mounted in a closed cylinder 25 connected as by means of a conduit 26 to the intake manifold 30 of the engine to be started. Since the 10 utilization of engine intake manifold vacuum for operating various types of devices is old and well-known, it is not thought to be necessary to further illustrate the engine structure.

In the operation of this embodiment of the 15 invention, closure of the manual switch 8 completes the control circuit for solenoid 7 through contacts 12, 13 whereby the starting switch 4 is closed and cranking takes place. When the 20 engine starts, the intake vacuum generated by the self-operation of the engine causes piston 24 to operate armature 14 to open contacts 12, 13 thus introducing solenoid 20 and resistance 22 into the control circuit. This causes solenoid 7 to be substantially deenergized and permits the 25 starting switch 4 to open. The contacts 12, 13 are thereafter held open by solenoid 20 as long as the manual switch 8 remains closed. It will be understood that the design and dimensions of the vacuum control are so arranged that the 30 control is ineffective to open contacts 12, 13 by the slight vacuum generated during cranking. This may be accomplished by making the re-

turn spring 27 of the armature 14 sufficiently strong for the purpose, or preferably by the use of a suitable spring 28 above the piston 24.

Although certain embodiments of the invention have been shown and described in detail, it will 5 be understood that various other embodiments are possible and changes may be made in the proportions and arrangements of the parts without departing from the spirit of the invention as defined in the claims appended hereto. 10

What is claimed is:

1. In a starter control for internal combustion engines, a magnetic starter switch, a control circuit therefor including a set of contacts, means responsive to intake vacuum of the engine when 15 the engine starts for opening said contacts, and electromagnetic means normally shorted by said contacts for holding the contacts open.
2. In a starter control for internal combustion engines, a magnetic starter switch, a control circuit therefor including a pair of contacts, means responsive to intake vacuum of the engine when the engine starts for opening said contacts, and a lock-out circuit bridged around said contacts and including means adapted when energized to 20 hold the contacts open, said lock-out circuit having sufficient resistance to insure the opening of the starter switch when the lock-out circuit is 25 cut into the control circuit by the opening of the contacts.

PAUL H. MAURER.
